(57) **CLAIM**

The ornamental design for a fuel supply device for fuel cell based charger, as shown and described.

DESCRIPTION

FIG. 1 is a front, bottom isometric view of a fuel supply device for fuel cell based charger according to the present invention.

FIG. 2 is a rear, bottom isometric view of the fuel supply device for fuel cell based charger of FIG. 1.

FIG. 3 is a front elevation view of the fuel supply device for fuel cell based charger of FIG. 1.

FIG. 4 is a rear elevation view of the fuel supply device for fuel cell based charger of FIG. 1.

FIG. 5 is a left side elevation view of the fuel supply device for fuel cell based charger of FIG. 1.

FIG. 6 is a right side elevation view of the fuel supply device for fuel cell based charger of FIG. 1.

FIG. 7 is a top plan view of the fuel supply device for fuel cell based charger of FIG. 1; and,

FIG. 8 is a bottom plan view of the fuel supply device for fuel cell based charger of FIG. 1.

The broken lines in the drawings illustrate elements of the fuel supply device for fuel cell based charger that form no part of the claimed design.
